UNITED STATES PATENT OFFICE.

WILLIAM E. THOMAS AND HARRY J. THOMAS, OF FLORENCE, SOUTH CAROLINA.

HYDROCARBON-BURNER.

1,386,448.

Specification of Letters Patent.

Patented Aug. 2, 1921.

Application filed July 27, 1920. Serial No. 399,231.

To all whom it may concern:

Be it known that we, WILLIAM E. THOMAS and HARRY J. THOMAS, citizens of the United States of America, residing at Florence, in the county of Florence and State of South Carolina, have invented new and useful Improvements in Hydrocarbon-Burners, of which the following is a specification.

10 The object of the invention is to provide a relatively simple and comparatively inexpensive burner adapted for use in connection with heating and cooking stoves and the like and serving as a means whereby the fuel such as kerosene, crude oil, etc., may be effectively vaporized prior to reaching the point of ignition so as to insure complete combustion and hence an economy in the consumption of the fuel, while minimizing 20 the deposit of carbon and hence the tendency of the apparatus to become choked and thus rendered inoperative; and with this object in view the invention consists in a construction and combination of parts, of which a 25 preferred embodiment is shown in the accompanying drawings, wherein:—

Figure 1, is a side view partly in section of a burner embodying the invention.

Fig. 2, is a sectional view on the plane indicated by the line 2—2 of Fig. 1.

Fig. 3, is a plan view of the same.

Figs. 4 and 5 are horizontal sections respectively on the planes indicated by the lines 4—4 and 5—5 of Fig. 1.

35 The apparatus embodies essentially a hollow base 10 consisting of a ring or band fitted with a cap plate 11 which is removable and is preferably provided with an embedded ignition tray or trough 12 which 40 may have a filling of asbestos or other refractory material as indicated in Figs. 2 and 4, as fuel chamber 13 formed in a casting 14 which is fitted in a seat 15 provided in the wall of said base, a vaporizing tube 45 16 and a burner tube 17. The fuel chamber is supplied with fuel by a feed pipe 18 fitted with a suitable valve 19 of the needle or other preferred type, it being preferable to supply the feed pipe with oil under pressure from either an overhead or elevated tank (not shown) or any equivalent thereof well known in the art and from said fuel chamber the oil flows through the vaporizing tube which is in communication therewith 50 55 and preferably consists of an elbow member 20 fitted at one end as by means of a thread-

ed joint 21 in the upper end of a fuel chamber and connected at the other end by means of a return coupling 22 with one end of a supplemental elbow pipe section 23 of which 60 the opposite end is connected by a coupling 24 with said burner tube. The burner tube is above and longitudinally of the initial ignition pan or tray 12 and is provided with an orifice 25 through which the fuel escapes 65 after having passed through the vaporizing tube. The outer end of the burner tube may be fitted with a removable cap 26 to permit of access for cleansing purposes when necessary.

70 Suspended by the supplemental elbow section 23 of the vaporizing tube is a deflector disk 27 preferably having ears 28 which engage the horizontal portion of said pipe section 23 and which serves to spread 75 the flame due to the combustion of the fuel, from the orifice 25.

In spreading the burner, the needle valve 80 may be opened until the vaporizing tube and burner tube have been filled and there has been sufficient overflow to the initial ignition tray or pan to permit of lighting the oil in said tray, whereupon the valve should be closed until the heat of the flame due to the burning of the oil in said tray has vaporized the fuel into tubes whereupon the needle valve may be again opened to continuously supply the burner tube, the fuel in its passage through the vaporizing tube due to the forward and backward runs of the motor 90 members of said tubes above the burner tube resulting in the vaporization of the fuel before it reaches the burner tube and thus presents the fuel at the orifice of the burner tube in condition for complete combustion. 95

The cap plate 11 is cut away or notched as indicated at 29 to fit around the lower end of the vaporizing tube to permit of the removal of said plate when required, and the upper edge of the wall of the base is 100 cut away to form an air inlet opening 30 from which the air in turn may escape at opposite sides of the tray or pan 22 through the outlet openings 31 formed in the cap plate beneath the burner tube. 105

It has been demonstrated in practice that a relatively crude fuel oil may be utilized economically in connection with the burner constructed as herein shown under conditions resulting in the maximum production 110 of heat and that owing to the manner in which the fuel is conducted to the burner

tube the choking or clogging of the latter by deposits of carbon and tar is practically eliminated.

Obviously, however, in view of the construction and relative connection of the parts or members constituting the structure, the cleansing of the same in the event of deposits can be readily accomplished by the disconnection of the same at the several joints provided, for example, between the members of the vaporizing tube and between the extremities of the vaporizing tube and the fuel chamber and burner tube respectively.

The invention having been described, what is claimed as new and useful is:

1. A hydro-carbon burner having a base provided with a fuel chamber and means for controlling the admission of fuel to said chamber, a vaporizing tube in connection with the fuel chamber and having a plurality of runs disposed in a common vertical plane in diametrical relation to and above the base and a burner tube in connection with the opposite end of said vaporizing tube and disposed beneath said runs of the vaporizing tube.

2. A hydro-carbon burner having a base provided with a fuel chamber and means for controlling the admission of fuel to the said chamber, a vaporizing tube in connection with the fuel chamber and having a plurality of runs disposed in a common vertical plane in diametrical relation to and above the base and a burner tube in communication with the opposite end of said vaporizing tube and disposed beneath said runs of the vaporizing tube, a deflector being interposed between the burner tube and the lowermost run of the vaporizing tube.

3. A hydro-carbon burner having a base provided with a fuel chamber, and a valve controlled means for supplying fuel to said chamber, a vaporizing tube consisting of main and auxiliary elbow sections connected

in series at one end, one end of the main elbow section being in communication with the fuel chamber and one end of the auxiliary elbow section carrying the burner tube, said main and auxiliary elbow sections having horizontal elements arranged in a common vertical plane in diametrical relation with and above the base and in a common plane with the said burner tube, and a flame spreader interposed between the burner tube and said horizontal elements on the elbow sections.

4. A hydro-carbon burner having a run consisting of an annular wall and a removable cap plate provided with a diametrically disposed initial ignition tray having a refractory filler and said base also being provided with a fuel chamber and valve means for admission of fuel to the chamber in combination with a vaporizing tube and a connected burner tube having elements arranged in a common vertical plane in diametrical relation with the base and above the said initial ignition tray.

5. A hydro-carbon burner having a run consisting of an annular wall and a removable cap plate provided with a diametrically disposed initial ignition tray having a refractory filler and said base also being provided with a fuel chamber and valved means for admitting fuel thereto and combining with a vaporizing tube and a connected burner tube having elements arranged in a common vertical plane in diametrical relation with the base and above the said initial ignition tray, and a flame spreader interposed between the said burner tube and those elements of the vaporizing tube which are arranged in a common vertical plane therewith.

In testimony whereof we affix our signatures.

WILLIAM E. THOMAS.
HARRY J. THOMAS.
